UNITED STATES PATENT OFFICE.

CHARLES BOUIN, OF BOSTON, MASSACHUSETTS.

CINEMATOGRAPHIC PICTURE WITH STEREOSCOPIC AND COLOR VALUES.

Application filed January 26, 1922. Serial No. 531,936.

To all whom it may concern:

Be it known that I, CHARLES BOUIN, a citizen of the United States, residing at Boston, in the county of Suffolk and State of Massa-

5 chusetts, have invented certain new and useful Improvements in Cinematographic Pictures with Stereoscopic and Color Values, of which the following is a specification.

This invention involves the arts of stereoscopic, motion picture and color photography, the three being combined, and with other features to be mentioned, constitutes an improvement of such combination. The invention relates more particularly to a 10 standard size motion picture film upon which are photographed images of scenes or objects, such images having stereoscopic and color values or qualities; one or more images of scenes or objects being contained within 15 a space area of one inch by $\frac{3}{4}$ inch, which is the standard space area ordinarily consumed for one image of scene or object in the present day moving picture film; each pair of stereoscopic left and right angle images 20 upon negative or positive moving picture film, being equal to or greater in distance from each other than the normal binocular distance and also having primary color values. Further objects and advantages 25 of the present invention will be pointed out in the hereinafter following description of one embodiment hereof, or will be obvious to those skilled in the mentioned arts.

Figure 1 is a fragmentary plan view of a 30 moving picture film strip showing in normal size right and left stereoscopic pairs of images and their color values.

Figure 2 is a similar view showing a modification of the arrangement of two images 40 occupying the normal single image space.

Figure 3 is a like view showing another modification of the disposition of four images in a single normal image space, the normal binocular distance of stereoscopic 45 pairs being preserved.

Figure 4 is another fragmentary view of another modification of the film strip illustrating the arrangement of eight images in the normal single image space.

50 Figure 5 is a view similar to Figure 2, further modified by the position of marginal edge markings of the stereoscopic pairs of images.

Figure 6 is a like view showing a modification of the form illustrated in Figure 3 adopting the edge markings of the same.

Figure 7 is a diagrammatic illustration of the relation of images spaced a binocular distance apart and with relation to the eyes; and

60 Figure 8 illustrates diagrammatically the relation of pairs of images photographed from equi-distant points but from different angles of direction.

65 Before describing the present invention in detail, it will be advantageous to refer to Fig. 7, which will better enable us to understand the following:— For the sake of explanation of the principle involved here, let it be understood that the normal distance of 70 the two eyes from each other is $2\frac{1}{2}$ inches; and, regardless of position of the head, the direction of the two eyes in relation to each other is always a horizontal direction. Now, this horizontal distance of $2\frac{1}{2}$ inches would 75 represent the horizontal differences in the two images which are presented to the retina of each eye, upon looking at an actual view with both eyes. This would be the normal amount of binocular differences in normal vision, such a condition would represent binocular or stereoscopic differences 100% efficient. In normal vision, regardless of the position of head, when looking at a natural scene, the binocular differences are at all 80 times presented to the retinae in a horizontal direction of the two eyes, which corresponds to the horizontal direction of the two eyes in relation to each other. In other words, when we look at a natural or original scene 85 or object, the only stereoscopic differences that the retinae are presented or impressed with, are the differences which are in the direction of the relation of the two eyes with each other, and such is necessarily so, simply because it so happens to be the position of the eyes, and in virtue of such being the case, regardless of position of the head, binocular differences in the images which are impressed upon the retinae are always 100% 90 efficient.

95 But such a condition as that just noted is not met with when we look at two stereoscopic photographs; the reason being that the only stereoscopic or binocular differences 100 in the two pictures or images are in one direction only and that direction of differences being corresponding to the relation of direction of the two positions of exposures during the time of photographing. Such 11 directions of differences in two photographic images remaining unchanged regardless of

the position that such photographic images may be placed in.

Referring to Fig. 7, A and A' or the horizontal line as indicated by 100 and 100' represents a true horizontal direction of the eyes in relation to each other; the points C and C' represents the normal distance of the two eyes, two images which have been photographed from two such distances as indicated by points D and D' and presented to the eyes in upright position, we would have the 100% stereoscopic differences presented to the retinae in such a manner that approximately 88% of such stereoscopic differences would be in horizontal alinement, or in other words, the 100% efficiency stereoscopic differences would be decreased approximately 12%. Should the horizontal distance of D to D' be increased, so would the stereoscopic or angle differences in the images become exaggerated or enhanced accordingly, and this enhancement is made use of in order to overcome the decreased amount of stereoscopic differences in the horizontal direction of line 100 to 100'. The mind being unable to perceive 100% of relief for the reason that stereoscopic differences which are presented to the retinae are approximately only 88% in the direction of the horizontal relation of the two eyes, when vertical or upright direction of images are maintained. The two images photographed from two different points as indicated in Fig. 7, by points D and D' would represent 100% efficient stereoscopic differences in such a direction with a decrease of approximately 12% from the horizontal direction as indicated by a comparison of the lines A to A' and D to D'. Now if two such images were brought in alinement maintaining their height and width in their original directions, we would still have stereoscopic differences varying from the true horizontal direction of the two eyes to the amount of approximately 12%. So, then, the qualities required for the perception of space etc., will be decreased 12%, leaving us with approximately 88% in the proper direction of binocular direction of perception of differences whereby perception of relief etc., occurs.

The deficiency of the 12% stereoscopic differences as has been explained, being overcome in the following manner, by increasing the distance of the two points from which the right and left pairs of images are photographed without increasing the vertical height of images, the angle direction approaches nearer to the horizontal direction of line 100 to 100', thereby decreasing the amount of 12% deficient; increasing the distance of the right and left exposure to the amount of 12% beyond the normal distance of the two eyes would give us 12% enhancement, thereby giving us perception of relief, space, etc., more than 88% efficient, or ap-

proximately 100% efficient. The smaller the vertical height of images as above described and at certain distances the less the requirement for increase of distance of right and left images for the purpose of 100% efficiency. 70

In further explanation, Fig. 8, is to be considered; the upper horizontal line is intended to represent the direction of binocular or stereoscopic differences and direction 75 of the two eyes in relation to each other. In looking at an actual scene with the eyes in position as indicated by the two points marked 100 and 100', the images upon the retinae are 100% binocular differences in this direction; now if two pictures are photographed from two points of the same distance, but from a different angle direction, such as the direction as indicated in Fig. 7, by the line D to D', maintaining 80 the upright position of such two pictures when brought into alinement in the horizontal direction of line A and A' in Fig. 7, or the upper line of Fig. 8, the stereoscopic differences would be decreased approximately 85 90 in the horizontal direction.

So, then, the points of distance and stereoscopic differences may be represented as in the lower horizontal line of Fig. 8. The two points D and D' in Fig. 7, being represented 95 by the two points marked 88 and 88' in lower line of Fig. 8. By increasing the distance of the two points D and D' in Fig. 7, to an amount equal to the percentage of decreased differences, such two points would be equal 100 in distance to the two points as indicated by 100 and 100' in lower line of Fig. 8. Here we would get 88% stereoscopic differences, plus 12% enhancement of such stereoscopic differences. 105

In this invention it is by such means as above stated that stereoscopic differences of left and right images are obtained upon the moving picture film, especially when the two points from which the images are photographed or the images upon said film are not in a true horizontal direction in relation to each other. 110

Further objects of this invention being to combine with the already mentioned 115 stereoscopic images, color values of such images which run in rotation, the color values being of either two or three primary colors.

In the different negative and positive 120 moving picture films which are representative of stereoscopic and color values as indicated by Figs. 1, 2, 3, 4, 5, and 6, the exposures for such images may be made intermittently or stereoscopic pairs may be 125 made at the same time of exposure. The relation of position of left and right pairs of images properly belonging to each other on film as indicated by corresponding numbers being a true representation of the di- 130

rection of stereoscopic differences, and also representing the distance of stereoscopic pairs from which they were photographed; such two different points, positions or horizontal distances in space corresponding to or being greater than binocular distances; the space area of one inch by $\frac{3}{4}$ inch containing either one, two, four, eight, or any even number of pictures or images, such images representing primary color values. The images representative of stereoscopic and color values being photographed upon a standard size film. The images of stereoscopic qualities being photographed through color screens for color values. All images of scenes or objects being on one and the same side of film.

The moving picture negative or positive film representative of stereoscopic and color values as indicated by Fig. 1 has one image of scene or object within the space area of 1 inch by $\frac{3}{4}$ in. The right and left angle images properly belonging to each other being in alinement across length of film horizontally and being separated by two spaces of 1 inch by $\frac{3}{4}$ inch each, each space being $\frac{3}{4}$ inch horizontally. Each right and left angle images properly belonging to each other being representative of different primary color values, which, in the positive film is not colored, dyed, or mordanted, for the purpose of projection with the aid of color screens; when color screens are not used in projection, such images upon positive film are either colored, dyed, or mordanted according and corresponding to the color values which each image represents. The two images (right and left stereoscopic images) representing the two different angle points of direction from which the images of scenes or objects are photographed. The right and left images representing two different primary color values, of scenes or objects. The images properly belonging to each other and also representing different primary color values, being in rotation and separated by two spaces of $\frac{3}{4}$ inch each horizontally as indicated in Fig. 1, by corresponding numbers, and, the differentiation of the right and left angle images by L and R respectively. Each image has four perforated holes on the edge of film and outside of image; the perforated holes being of standard size, shape and distance from each other; in each image and stereoscopic and color valves are photographed at one and the same time; the left angle images have marks of identification on lower edge of film and right angle images have marks of identification on upper edge of film.

The moving picture negative or positive film as indicated in Fig. 2, has two images of scene or object within or occupying a space area of one inch by $\frac{3}{4}$ inch; the right and left angle images or stereoscopic pairs

properly belonging to each other are separated by two or more spaces of one inch by $\frac{3}{4}$ inch; each space being $\frac{3}{4}$ inch horizontally. Corresponding pairs of stereoscopic images being in position and relation to each other as indicated by corresponding numbers in Fig. 2.

In all the different styles of film as indicated by Figs. 1 to 6, all right and left stereoscopic pairs of images, as indicated by corresponding numbers, are representative of different primary color values, which, in the positive film are not colored, dyed or mordanted when the projection of such images is accomplished with the aid of color screens; when color screens are not employed in projection of said images, the images upon positive film are either colored, dyed or mordanted, according and corresponding to the color value which each image represents.

In the styles of film as indicated by Fig. 1 and Fig. 2, all images representing those photographed from one angle point or position are below horizontal centre of film and in direction of length of film and all images representing those photographed from another angle point or position, are above horizontal centre of film, and in direction of length of film, as indicated by numbers in rotation.

In all the different styles of film mentioned in this invention, the position on film of the right and left pairs of stereoscopic images represent the two different angle points of position, direction and distance from which such images are photographed. In Figs. 2, 3, 4, 5, and 6, every three right angle images in rotation represent three different primary color values, one primary color value to each one of these three images, each one of the three images being possessed each of a different primary color value of scene or object and likewise with the left angle images.

In Figs. 1, 2, and 5, each image has four perforated holes on edge of film and outside of image; in Figs. 3, 4, and 6, each image has two perforated holes on edge of film and outside of image. The perforated holes on edges of film being of standard size, shape and distance from each other. All images being on one side only of film.

In Fig. 1, only one image of scene or object occupies the space area of one inch by $\frac{3}{4}$ inch; in Figs. 2 and 5, two images of scene or object occupy a space area of one inch by $\frac{3}{4}$ inch; in Figs. 3, and 6, four images of scene or object occupy a space area of one inch by $\frac{3}{4}$ inch; in Fig. 4, eight images of scene or object occupy a space area of one inch by $\frac{3}{4}$ inch.

When more than one image of scene or object are contained within the same space area of one inch by $\frac{3}{4}$ inch, such two or

more images within the same space area of one inch by $\frac{3}{4}$ are not stereoscopic pairs properly belonging to each other; the right and left stereoscopic pairs of images properly belonging to each other being located in different space areas of one inch by $\frac{3}{4}$ inch.

In all the different styles of film mentioned the right and left angle or stereoscopic pairs have a distance of separation which is equal to or more than the normal distance of the two eyes in relation to each other.

I do not confine myself to the particular style of film or position of images here shown, but various other changes and modifications, within the skill of those versed in the art, may be made in the different styles of film images and positions of such images shown and described herein, without departing from the spirit of my invention provided the principle set forth in the following claims be employed.

Having thus described my invention, I claim:—

1. A motion picture film comprising a

body portion having photographed thereon stereoscopically images of scenes and the like contained within the standard space area, each stereoscopic pair of left and right angle images having respective distinguishing natural color values and being spaced apart a distance greater than the normal binocular distance and having stereoscopic differences laterally greater than normal.

2. A motion picture film comprising a body having photographed stereoscopically therein images of scenes and the like with such photographs spaced a distance apart greater than the normal binocular distance and having the combined area of the standard sized motion picture photograph and having stereoscopic distances laterally greater than normal, said images of scenes and the like having distinguishing primary color values with respect to the right and left angle images.

This specification signed this 19th day of January, 1922.

CHARLES BOUIN.
